DOMESTIC APPLIANCE

John B. Dyer, Dayton, Ohio, assignor to General Motors Corporation, Dayton, Ohio, a corporation of Delaware

Application May 26, 1939, Serial No. 275,950

1 Claim. (Cl. 68—97)

This invention relates to a domestic appliance and more particularly to washing machines in which the washing, rinsing and drying operations are performed in a single tub.

The trend in washing machines is toward reduction in labor in washing and drying and simplification of the mechanism, particularly there is a trend toward washing machines in which the washing, rinsing and drying operations are performed within a single container. In some recent washing machines, agitation means has been provided within a centrifugal drying receptacle in accordance with this trend so that washing and drying may be accomplished without the transfer of the clothes during the washing operation. Such washing machines require considerable expensive mechanism, especially because the agitating means must be operated at a relatively slow speed and the centrifugal drying receptacle must be operated at high speed. Therefore two sets of drive mechanisms are required and this makes the machinery and the completed cost of the washing machine more expensive than most families can afford.

It is therefore an object of my invention to provide a simple inexpensive washing machine in which the washing, rinsing and drying operations can be accomplished in the same receptacle without transfer or handling of the material being washed.

It is another object of my invention to provide a washing machine in which the same mechanism is used for performing the washing, rinsing and drying operations.

It is another object of my invention to provide a washing machine which operates at the same speed for washing, rinsing and drying.

It is still another object of my invention to provide a washing machine in which the washing, rinsing and drying operations can be satisfactorily performed in a much shorter period of time.

It is another object of my invention to provide a washing machine which requires the use of less hot water and less rinse water.

It is another object of my invention to provide a washing machine with an improved washing, rinsing and drying mechanism having little tendency to vibrate and which operates at a relatively slow speed without requiring excessive gear reduction or creating great stresses.

Further objects and advantages of the present invention will be apparent from the following description, reference being had to the accompanying drawings, wherein a preferred form of the present invention is clearly shown.

In the drawings:

Fig. 1 is a vertical sectional view of a washing machine embodying one form of my invention;

Fig. 2 is a sectional view taken along the lines

5 2—2 of Fig. 1; and

Fig. 3 is a sectional view taken along the lines

3—3 of Fig. 1.

Brief description

Briefly, my washing machine involves as its 10 essential elements a roller with a rubber covered surface which rolls upon the inner surface of a container or receptacle having a cylindrical wall. The axis of rotation may be in any plane but as shown the container or receptacle is in the form of a tub which is rotatable about its central vertical axis. The bearing for the rotatable tub is resiliently supported and the rubber covered roller member is driven by an electric motor and held in engagement with the side wall of the tub 15 which is supported by another set of rollers which serve to back up the side wall of the tub and prevent strain upon the resiliently supported bearing.

20 The clothes to be washed are placed within the tub with a suitable amount of hot water and soap and both rollers and the tub are rotated and the clothes are pressed against the sides of the tub by the roller and thus the water is squeezed out every revolution so that the clothes are thoroughly washed by this method. A centrally located drain connection is provided through which the water may be drained from the tub and rinse water can then be introduced preferably just in 25 advance of the roller. The operation of the tub 30 may be continuous and water introduced and drained while the tub and roller are in rotation. After the final rinsing the tub is drained and the operation of the tub and roller is continued until substantially all of the water is squeezed out of the clothes.

The tub

Referring now to the drawings there is shown a washing machine generally designated by the 35 reference character 20 including a tub 22 having a cylindrical side wall and a bottom wall which is sloped downwardly to its center portion where the outer shell of the tub is connected to a hollow bearing pin 24 provided with a passage 26 for 40 draining the tub. The passage 26 is provided with a rubber stopper 27 or some other suitable means for closing the passage 26 when it is desired to retain water in the tub. The bearing pin 24 is provided with a shoulder portion and 45 a sleeve portion which are supported by the bear-

ing 28. The bearing 28 is provided with an upper flange portion which provides a bearing support for the flanged portion of the bearing pin 24. The bearing 28 also has a cylindrical portion which receives and provides a bearing for the hollow pin portion of the bearing pin 24. Beneath the bearing 28, the bearing pin 24 is provided with a collar 30 which is fastened by a set-screw so as to lock the bearing pin 24 within the bearing 28.

The flanged portion of the bearing 28 is supported by a heavy ring 32 of a rubber-like material such as properly compounded soft rubber. This ring 32 is supported upon a metal ring 34 which is welded to flanged arms 36 which extend radially outwardly to a skirt ring 38 located immediately beneath the tub 22 and formed in substantially the same shape. These arms 36 are fastened by the screws 40 to the legs 42 and 44 of the washing machine. Beneath the metal ring 34 is another heavy ring 46 of a rubber-like material beneath which there is provided a metal ring 48. Screws 50 extend through the metal ring 48, the two rubber rings 32 and 46 and through large holes in the ring 34 and are threaded into the flange of the bearing member 28 in order to provide a resilient mounting for the bearing 28 which will hold the tub in place during all normal conditions of loading.

The motor and roller support

The leg 44 also supports the driving mechanism of the washing machine. At the upper end, this leg 44 is provided with a yoke 52 having a pin 54 extending between its arms. This pin pivotally connects the yoke 52 to the motor and roller support as designated by the reference character 56. This yoke 52 is normally locked with its upper face in a horizontal position by a locking lever 58 pivotally connected by the pin 61 to the outer portion of the casting 56 and is provided with the locking shoulder which engages the bottom of a notch provided in the upper portion of the leg 44. Bolted to the upper face of the casting 56 by the screws 60 is an electric motor 62 having a vertical axis and provided with thrust bearings for operating in this position. This motor drives a small pinion 64 within the gear case portion 66 of the casting 56.

The epicyclic gear train

This gear case portion 66 includes an epicyclic gear train for reducing the speed of the motor 62. This epicyclic gear train includes three gears 68, which are rotatably mounted upon pins provided in a three lobed member 70. These gears mesh on the inside with the pinion 64 and on the outside with a ring gear 72 which is fixed within the gear case portion 66. The three-lobed member 70 is provided with a pinion directly beneath the pinion 64 which meshes with a similar set of gears 78 which in turn mesh with another ring gear also formed within the gear case portion 66. These gears 78 are rotatably mounted on pins provided in a second three-lobed member 80 which is keyed to the upper end of the roller shaft 82.

The roller and shaft

This roller shaft 82 is supported by bearings provided at the upper and lower ends of a shaft casing 84 which extends downwardly from the gear case portion 66 and is an integral part of the casting 56 pivoted upon the pin 54. The lower end of the shaft casing 84 is provided

5 with an oil seal and the shaft 82 is provided with oil grooves for carrying the lubricant upwardly in the bearing portions located at the upper and lower portions of the shaft casing 84.

10 A heavy metal disc 86 is fastened to the lower end of the shaft 82 by a key and a nut. This disc 86 is connected to the roller 88 by six rods 90. The rods 90 pass through holes on the disc 86 and are locked in place by the set-screws 91. The upper and lower ends of the rods 90 are connected to the peculiarly shaped brackets 92 which are fastened to the inner metal wall 94 of the roller 88. These brackets 92 are formed of an angle shape with the horizontal portion of the angle turned back. This turned back portion serves as a stop for the ends of the rods 90 which extend through holes in the other portion of the bracket. The rods 90 are formed of resilient steel, such as spring steel or stainless steel and provide a resilient support for the roller 88 to correct for the inequalities of the wash which passes between it and the cylindrical side wall of the tub 22. In order to further correct for these inequalities of the material being washed the roller 88 is provided with a very thick covering of very soft rubber 96 or other suitable material.

15 In order to prevent the squeezing action between the roller 88 and the side wall of the tub 22 from producing a strain at the bearing 28, there is a set of rollers 98 provided upon the outside of the tub 22 which bear against the outside of the tub 22 directly on the other side of the wall from the roller 88. This set of rollers 98 is shown as formed of four wooden rollers 20 which are rotatably mounted upon a rod 110 fastened to bosses extending from the leg 44. However, these rollers may be made of other materials and may be provided with any suitable type of bearing support. If desired instead of driving the roller 88, the motor 62 may be arranged either above or below the tub 22 in order to drive the rollers 98 or even the tub 22. If any sort of difficulty occurs and it is desired to stop the action immediately the latch 58 may be pulled outwardly in order to permit the casting 56 to pivot in a clockwise direction about the pivot point 54.

Operation

25 In operation, the tub 22 may be filled with a hot soapy detergent washing solution and the clothes, fabrics and other articles to be washed are placed therein. A nozzle 112 may be provided for introducing water into the tub. The motor 62 is then started in operation and its speed and the gear reduction provided in the epicyclic gear train as well as the size of the roller 88 are so selected that the tub 22 will make about five and one-half revolutions per minute. The clothes will be squeezed against the cylindrical side wall of the tub 22 by the roller 88 and each time the clothes pass between the roller 88 and the side wall of the tub the water will be squeezed out, after which during the remainder of the revolutions of the tub the wash water will again soak into and saturate the clothes. This alternate squeezing and soaking of the clothes provides an effective washing operation. The roller 88 is sufficiently large and its rubber coating 96 is sufficiently thick and soft that the clothes are not damaged by this slow speed squeezing operation. It has been found that the clothes are thoroughly washed in about one-half the length of time required by present-day washing machines.

Following this, without stopping the motor 62, the stopper 27 may be pulled and the tub 22 drained. Practically all of the wash water is squeezed out of the clothes by the roller 88 by the time the tub 22 is drained. The stopper 27 is then replaced and rinse water introduced through the spout 112 which discharges rinse water upon the clothes just before they are squeezed by the roller 88. After a number of revolutions of the tub 22 the stopper is again removed and the first rinse water is drained. During this time substantially all of the first rinse water is squeezed from the clothes. The stopper 27 is then replaced and a second rinse water is introduced through the spout 112 and the clothes are thoroughly rinsed by the continued operation of the motor 62. After this the stopper 27 is again removed and the motor 62 continues to operate until the clothes are squeezed or wrung sufficiently dry to be removed. The motor 62 is then stopped and the clothes are removed ready to be hung up for drying.

It will be seen that to perform a washing by this washing machine the only operations required are the introduction and removal of the wash water and the rinse water. The motor and the washing, wringing and drying means may operate continuously and need only be started and stopped at the beginning and the end of the washing. Other than this it is only necessary to introduce and remove the material to be washed at the beginning and at the completion of the washing.

It will also be evident that this washing machine is provided with a simple mechanism and that the attention required and the labor involved in performing a washing is kept at a minimum. The size of the tub 22 may be kept small

and in this way the amount of water required may be kept small. The roller 88 displaces a certain amount of water and this also reduces the amount of water required. The depth of water required in the tub 22 is also less than is required for other types of washing machines. Because of the slow speed of operation of the tub 22 and the roller 88 there is substantially no vibration. The resilient support for the roller 88 and the tub 22 prevents great stresses upon the bearings and although the washing, rinsing and drying is performed by a squeezing operation the pressure employed in squeezing is not great and therefore the mechanism is not subject to great stresses on account of this method. Furthermore, stresses are reduced because of the slow speed of operation which avoids any substantial centrifugal force.

While the form of embodiment of the invention as herein disclosed, constitutes a preferred form, it is to be understood that other forms might be adopted, all coming within the scope of the claim which follows.

What is claimed is as follows:

A washing machine including a rotatable washing receptacle member, a rotatable roller member within said receptacle in rolling engagement with a wall of said receptacle member whereby the material to be washed is required to pass between said roller member and said wall, a second rotatable roller member outside said receptacle in rolling engagement with the outside of said wall and located adjacent the other roller member adjacent the region where the material to be washed passes between said first roller member and said wall.

JOHN B. DYER.
